[57] CLAIM

The ornamental design for a wire soap dish, as shown and described.

DESCRIPTION

FIG. 1 is a perspective view of a wire soap dish showing our new design, the suction cups shown in phantom lines not forming part of the invention;

FIG. 2 is a top plan view thereof;

FIG. 3 is a bottom plan view thereof;

FIG. 4 is a front elevational view thereof;

FIG. 5 is a right side elevational view thereof;

FIG. 6 is a rear elevational view thereof;

FIG. 7 is a left side elevational view thereof.

FIG. 8 is a perspective view of an alternative embodiment of a soap dish showing our new design;

FIG. 9 is a top plan view of the embodiment as shown in FIG. 8;

FIG. 10 is a bottom plan view of the embodiment as shown in FIG. 8;

FIG. 11 is a front elevational view of the embodiment as shown in FIG. 8;

FIG. 12 is a right side elevational view of the embodiment as shown in FIG. 8;

FIG. 13 is a rear elevational view of the embodiment as shown in FIG. 8; and,

FIG. 14 is a left side elevational view of the embodiment as shown in FIG. 8.
